UNITED STATES PATENT OFFICE.

WALTER EAMES BLOUNT, OF WASHINGTON, DISTRICT OF COLUMBIA.

STATION MAIL-BAG CATCHER.

No. 869,132.

Specification of Letters Patent.

Patented Oct. 22, 1907.

Application filed August 3, 1907. Serial No. 386,958.

To all whom it may concern:

Be it known that I, WALTER EAMES BLOUNT, a citizen of the United States of America, residing at Washington, in the District of Columbia, have invented certain new and useful Improvements in Station Mail-Bag Catchers, whereof the following is a specification.

This invention relates to a mail bag or pouch catcher for use at railway stations for catching the bags or pouches from rapidly moving trains, as contradistinguished from catchers disposed in mail cars for grabbing such pouches or bags from the stationary supports on which they are hung at the stations along the route.

The object of the invention is to provide a simple apparatus which will gradually absorb the momentum of the flying bag and deliver it without injury at the station.

Figure 1 of the accompanying drawings represents a perspective view of one form of this mail bag catcher and a mail car in the act of delivering a mail bag thereto. Fig. 2 represents on a small scale a top plan view of a catcher and the car delivering device about to deliver a bag thereto. Fig. 3 represents also on a similar scale a front elevation of a catcher showing the course along the catcher of bags of different weights or bags delivered at different speeds. Fig. 4 represents a plan of a reversible mail bag catcher embodying this invention and adapted for single track railroads, being adjustable to different positions for catching bags delivered from trains moving in either direction. Fig. 5 represents a side elevation of a reversible catcher. Fig. 6 represents an enlarged horizontal section of the swivel joint of a reversible catcher. Fig. 7 represents a side elevation of a reversible catcher. Fig. 8 represents a horizontal section of a buffer in the form of a volute scroll affording a path for the bag of more than a complete circle.

Similar reference numbers indicate corresponding parts in the different figures.

This station mail bag catcher comprises, in the form herein illustrated, a platform or base 10 onto which the mail bag is finally delivered, a post 20 and a buffer 30 secured to said support and adapted to catch the bag from the delivery apparatus on the car and discharge it in a quiescent state without injury onto said platform.

The base 10 may be in the form of a metallic plate secured to the station platform or to sills anchored in the ground near the station.

The post 20 is preferably constructed of two T-shaped steel bars bolted together head-on, said bars being firmly secured to the base 10 and provided with truss rods 21, or other suitable bracings.

The buffer 30 has a concave face 31, preferably disposed vertically, against which the bags roll or slide after delivery from the car. This active concave face is so shaped as to present a gradually increasing re-

sistance to the motion of the bag and is of such length as to completely absorb, or nearly so, the momentum thereof. The resistance face of the buffer is preferably in the form of a volute curve having its end 31' of 60 greater radius projected in the path of the bag to be caught, and provided at its end of smaller radius with a vertical pocket 32 formed by the inner arc of the curve. This pocket constitutes a stop for the bag which drops therefrom by gravity to the platform or base 10. The 65 buffer is preferably provided on its lower edge with a guide flange 33 which is preferably inclined downward toward the point of delivery, and may extend from the receiving end 31 to the pocket 32. This flange is designed to support and guide to the proper delivery 70 point bags of less than the maximum weight or momentum and the buffer is preferably of greater depth at its delivery end to permit the gradual fall of the lighter bags during their passage along the curved face of the buffer. The buffer is constructed of steel or other 75 suitable material and is provided with suitable strengthening means, for instance with ribs 34 disposed on the back thereof.

The connecting mechanism between the buffer 30 and its support 20 is preferably such as to permit a 80 vertical adjustment thereof and also a horizontal adjustment toward and from the railway track. The means shown for this purpose comprises one or more looped straps 22, the looped ends of which are adapted to slide on the post 20, said loops being provided with 85 set screws or bolts 25 which engage the post or holes therein.

The buffer is provided at its back with steel straps 35 which are secured to the looped straps 22 by means of bolts 26 or other means. One set of straps 90 is provided with slots 36 which permit the horizontal adjustment of the buffer for the purpose aforesaid. Means are preferably provided for bracing the buffer at the rear thereof so as to insure its withstanding the force of the heaviest bags at the highest momentum. 95 The means shown for this purpose comprise in Figs. 1, 2 and 3 a stationary brace 40, preferably of triangular shape, having its broad end secured to said buffer at the back thereof and its apex anchored to the earth.

The mail car is provided with a suitable delivery 100 device for delivering the bag from the moving train to the buffer 30. This delivery device may be of any suitable construction adapted for this purpose. In the form shown it comprises a swiveled horizontal delivery arm 50 attached and braced to a post 51 journaled in 105 supports 52 and 53 in the door way of the mail car and provided at its outer end with a spring clamp 54 or other means for holding the mail bag hanger and permitting it to slide off the end of said arm. The arm is swung into the car when not in use and is swung 110 outward and projects laterally from the car for delivering the bag which is hung thereon for that purpose.

The delivery arm is preferably so disposed as to avoid interference with a catcher 60 for taking bags aboard the car from stations along the route.

A mail bag catcher for stations made reversible to adapt it for use for catching bags from trains in either of two directions, is illustrated in Figs. 3, 4, 5 and 6. In this case a buffer 70 having a curved volute concave resistance face 71, similar to the face 31 of the buffer 30, is provided at its pocket end on its outer face with a disk 72 which is preferably integral with the buffer. This disk is provided with a central pivot socket 73 and with locking holes 74 and 75. An angle iron bar 80 is adjustably connected by bolts with an eye bar 22 adjustable on the post 10 and is provided at its outer end with a disk 81 against which the swiveled disk 72 of the buffer 70 is adapted to turn. The fixed disk 81 is provided with a pivot stud 82 which engages the pivot socket 73 of said swiveled disk 72, and with a hole 83. A locking pin 84 is held in hole 83 by means of a spring 85. A circular flanged ring 86 preferably composed of two sections connected by a hinge 87 and provided with a locking device 88 is designed to fit around the outer edges of the disks 72 and 81, and hold them firmly against straps and permit one to turn on the other.

The buffer 70 is adjusted to take mail from a train passing from left to right when in the position shown in full lines in Figs. 4, 5 and 6. It may be reversed to the position shown in dotted lines in Fig. 4 so as to take mail from trains passing from right to left, by pulling out the locking pin 84 from the hole 75 so as to release the swivel disk 72 and then turning said disk until the hole 74 registers with the hole 83 in the fixed disk 72. Then the locking pin 84 springs into the hole 74 and locks the buffer 70 in this position. To readjust the buffer 70 to the position shown in full lines in Figs. 1 to 4, the spring pin is again released and the disk is turned back. Thus the buffer may be easily and quickly reversed by an unskilled attendant.

The reversible buffer 70 is broadened vertically in both upward and downward directions from its taking-on end to its delivery end, and is provided with flanges 76 and 77 at both its edges so that the buffer will have a guide for light weight bags when it is in either position. Separate braces are provided for the reversible buffer, these braces being disposed at proper distances therefrom, and being preferably adjustable into and out of operative position. Any suitable braces for this purpose may be employed. The braces shown in Fig. 4 are adjustable into and out of operative position. A post 90 firmly set and braced is disposed at a proper distance at the left of the reversible buffer and a similar post 100 is disposed at the right of said reversible buffer. A brace 91, preferably of triangular form, is hinged to swing horizontally on the post 90 and is adapted to engage the back of the buffer 70 when the latter is adjusted in dotted line position for catching bags from a train moving from right to left and is swung at right angles to disengage said buffer. A similar triangular brace 101 is pivoted to the post 100 and also adapted to swing at right angles. This brace when in holding position is swung against a lug 78 on back of the buffer 70 and held there in locking position by a spring 79 attached to said buffer.

The operation will now be described. The catcher

30 or the reversible catcher 70, whichever is employed, is adjusted into proper position with reference to the path of the moving mail bag to be delivered. Before the train reaches the station where the delivery is to be made the mail clerk hangs the mail bag or pouch 110 70 to be delivered on the outer end of the delivery arm 50. The ordinary mail pouches are provided with metal eyes 111 and 112 respectively at their top and bottom and to facilitate the delivery by this mechanism there should be added to these metal eyes swivel sockets 113 75 and 114 respectively to permit the bag to turn or roll freely. The arm 50 on which the bag is hung by its swivel eye is swung outward into the position shown in Figs. 1 and 4, and the bag is then in position to engage the outer end of the buffer 30 or 70, as the case may be. 80 As the mail car passes the buffer the delivery arm 50 carrying the bag passes over the top of the buffer and the bag comes in contact at the outer end of the buffer with the concave face thereof, which diverts the bag and strips it off the end of said arm. The curvature of 85 said face gradually increasing in intensity affords a gradually increased resistance which absorbs or overcomes the momentum of the bag. The bag passes along this curved surface until it reaches the inner or pocket end thereof where it is finally arrested in its motion and 90 permitted to drop by gravity onto the platform. The gradual resistance offered to the force of the bag arrests the movement thereof without shock or impact and without injury to the bag.

In Fig. 8 the buffer is in the form of a volute scroll 95 involving more than one complete turn and affording a long curved resistance face for the traverse of the bags disposed in a compact space. In this case the flange at the bottom of the buffer is preferably dispensed with so as to leave the bags free to drop by gravity at any point 100 where the momentum thereof becomes exhausted. The volute wall where it doubles on itself is so arranged as to afford ample space for the passage of the bags in any form. This buffer is especially well adapted to a wide range of bags of different sizes delivered at different speeds and it occupies a comparatively small space at the station. 105

The buffer has preferably a maximum capacity for absorbing the momentum and arresting the motion of a bag of 200 pounds weight traveling at a speed of sixty 110 miles an hour. The same apparatus will with equal facility arrest the motion of bags of less weight or momentum.

The buffer, which is preferably volute, has a backward or return bend, and when rolled in upon itself so 115 as to describe one or more complete and overlapping turns, it affords sufficient resistance within a compact space to overcome the momentum of bags of various weights delivered at various velocities; and the buffer being disposed in vertical or substantially vertical position, gravity is permitted to act upon the bag to discharge it wherever its momentum becomes exhausted at any point along the face of the buffer, if the bottom flanges be omitted.

Two classes of receptacles are now commonly used 125 for inclosing mail matter, those called pouches for first class matter and those called bags for second and third class matter. The bags are not now provided with eyes or handles and have not heretofore been taken on or delivered on the fly. These bags for the purposes of 130

flying delivery will be provided with swivel eyes preferably attached to the bottom thereof at or near the center.

For the general purposes of this specification the words bag and pouch may be considered as equivalents of each other.

I claim as my invention:

1. A mail bag catcher provided with a curved buffer face having a gradually increased resistance which extends through a path adapted to absorb the entire momentum of the bag. 10
2. A mail bag catcher having a resistance face in the form of a volute curve for engaging the flying bag. 15
3. A mail bag catcher having a curved face of continuously increasing resistance and a delivery pocket at the inner end of said face. 15
4. A mail bag catcher having a continuous curved face of increasing resistance, a delivery pocket at the inner end of said curve, and a guide flange at the lower end of said face. 20
5. A mail bag catcher having a curved face of continuously increasing resistance, a delivery pocket at the inner end of said face, and a guide flange inclined toward said pocket. 25
6. A mail bag catcher comprising a reversible buffer having a return-curve bag-arresting face of increasing resistance. 30
7. The combination of a mail bag catcher comprising a buffer having a concave bag-arresting face of increasing resistance, and means for adjusting said buffer vertically. 30
8. The combination of a mail bag catcher comprising a buffer having a concave bag-arresting face of increasing resistance, and means for adjusting said buffer horizontally. 35
9. The combination of a mail bag catcher comprising a buffer having a concave bag-arresting face of increasing resistance, and means for adjusting said buffer vertically and horizontally. 35
10. The combination of a mail bag catcher comprising a buffer having a concave face embracing a backward curve of increasing resistance and means for bracing said buffer. 40
11. A mail bag catcher comprising a reversible buffer having a volute resistance face and guide flanges at its upper and lower edges. 40
12. A mail bag catcher comprising a reversible buffer having a volute resistance face and guide flanges at its upper and lower edges respectively, said flanges being inclined in opposite directions. 45
13. The combination of a buffer having a volute resistance face for overcoming the force of flying bags delivered thereonto, means to permit the reversal of said buffer to engage bags delivered in either direction and adjustable braces for holding said buffer in either position. 50
14. A mail-bag catcher provided with a buffer-face adapted for the bodily contact of the bag, said face having a curve of gradually decreased radius. 55
15. A mail-bag catcher comprising a buffer having a concave face of gradually increased resistance, and including a backward bend. 55
16. A mail-bag catcher comprising a buffer having a concave face of gradually increased resistance including a return bend. 60
17. A mail-bag catcher having a resistance face in the form of a volute curve involving a full turn. 65
18. A mail-bag catcher having a resistance face in the form of a volute curve involving a plurality of turns. 65
19. A mail-bag catcher having a vertical buffer-face disposed in a volute scroll and adapted to absorb the momentum of the bag. 70
20. A mail-bag catcher having a vertical resistance face disposed in a volute scroll and provided at its inner end with a vertical pocket. 70
21. A mail-bag catcher comprising a reversible buffer having a volute resistance face. 75
22. A mail-bag catcher having a curved resistance face which describes an overlapping turn adapted to absorb momentum of bags of various weights and various velocities, said resistance face being disposed in substantially vertical position, whereby the bag is discharged by gravity at any point of said face where its momentum becomes exhausted. 75
23. A mail-bag catcher provided with a curved buffer face adapted for the bodily traverse of the bag, the resistance of said face increasing in intensity from the point of contact of the bag to the point of delivery thereof. 80
